FIG. 3.

Frank J. Waite
Inventor

By his Attorneys,

Cadmore & Co.

UNITED STATES PATENT OFFICE.

FRANK J. WAITE, OF LEADVILLE, COLORADO.

PILLOW-SHAM HOLDER.

SPECIFICATION forming part of Letters Patent No. 451,588, dated May 5, 1891.

Application filed December 6, 1890. Serial No. 373,778. (No model.)

To all whom it may concern:

Be it known that I, FRANK J. WAITE, a citizen of the United States, residing at Leadville, in the county of Lake and State of Colorado, have invented a new and useful Pillow-Sham Holder, of which the following is a specification.

This invention is an improvement in pillow-sham holders, and has for its objects to provide a pillow-sham holder which will be adjustable in reference to the bed, and which will be convenient in use; furthermore to provide a pillow-sham holder which will be simple, cheap, and elegant in appearance.

With these objects in view the invention resides in the various novel details of construction, and in the combination of parts hereinafter fully described, and particularly pointed out in the claims.

In the drawings in which I have illustrated my invention, and in which like letters of reference indicate corresponding parts, Figure 1 is a perspective view of a bed having my pillow-sham holder attached. Fig. 2 is a detail view showing one form of my holder. Fig. 3 is a detail view of another form of my holder. Fig. 4 is a plan view of the construction shown in Fig. 1.

In the drawings, the letter A designates a bedstead having a head-board B, which is provided with the screw-eyelets C. Attached to the screw-eyelets and adjustable in relation to the head-board is a pillow-sham holder D. This pillow-sham holder is composed of a single piece of wire d, which, as shown in Fig. 2, has the central portion coiled, as shown at d', and within the length of this coil formed into eyelets d''. Beyond this coil d' the wire d is bent at right angles and formed into eyelets, and, making an outward loop d'', each end is brought downward, looped, and bent at right angles again, as shown at d⁴, and the ends d⁵ brought inwardly toward each other and their extremities formed into eyelets d⁶, embracing the opposite end; or the said wire d may be bent, as shown in Fig. 3—that is, one end, having been formed with a hook d⁷, is brought down, bent at right angles d⁸, formed into a curve d⁹, brought back to the right angle d⁸, looped thereabout, as shown at d¹⁰, and extending toward the right is formed into another curve d¹¹, which inter-

laces with the curve d⁹, and extending to the right beyond said curve d¹¹ forms interlacing curves d¹² and d¹³, and extending to the right 55 from the upper portion of the curve d¹³ is formed into a loop d¹⁴, brought downward and formed into a curve interlacing with the curve d¹³, and the end brought up and passed through the loop d¹⁴, and beyond said loop 60 bent into a right angle, carried upward, and formed into a hook d¹⁵. It will be seen that the hooks d⁷ and d¹⁵ form the ends of the single wire d, and that the length of the wire, formed as above described, in the interlacing 65 curves, will make a spring which will be to a limited extent capable of being adapted to beds of various sizes.

In practice I mount this pillow-sham holder D, which is composed of a single wire d, and 70 is of the form shown in Figs. 2 and 3, upon the head-board by attaching the hooks of one form of the spring to the eyelets C, or catching the body of said wire within said hooks in the other form. It will be observed that 75 both of my forms are adjustable to slight differences in the size of beds. In the one case the coiled spring and the embracing eyelets on the ends of the wire will permit longitudinal movement to suit bedsteads of any ordinary width, and in the other case the spring-body itself, formed by the interlacing curves, will permit of longitudinal extension or contraction to a limited degree.

I provide my pillow-sham holder D with 85 the pins or sham-hooks E, which may be placed at any suitable or convenient parts of the holder.

In using the form shown in Fig. 2 the sham will be given an elegant curve by the coiled 90 central portion d' at the top, and in using either of the forms shown the sham will be securely and properly held thereon.

The eyelets d² not only afford retaining devices for the pins E, but as the sham-holder 95 D is raised at right angles to the head-board the said eyelets will be pressed against the head-board by the spring and support the sham-holder. Other supporting or raising devices may be used, if desired.

Having thus described my invention, what I claim as new, and desire to secure by Letters Patent, is—

1. In a pillow-sham holder, the combina-

tion, with eyelets attached to the head-board of a bedstead, of a single wire connected with and journaled in said eyelets and between them formed into a spring and a sham-holding frame, substantially as and for the purpose set forth.

2. In a pillow-sham holder, the combination, with eyelets attached to the head-board of a bedstead, of a single wire connected and journaled in said eyelets, and between them being formed into interlacing curved portions which provide a spring and a sham-holding frame, substantially as and for the purpose set forth.

15 3. In a pillow-sham holder, the combination, with the eyelets C, of the wire D, having one end formed into a hook d^7 , bent at right angles to d^8 , formed into a curve d^9 , brought

back to the right angle d^8 , looped thereabout, as shown at d^{10} , and extending toward the right is formed into interlacing curves $d^{11} d^{12}$ d^{13} , and extending to the right of the upper portion of the curve d^{13} is formed into a loop d^{14} , brought downward, formed into curve d^{15} , and the end brought up and passed through the loop d^{14} , and beyond said loop bent into a right angle, carried upward, and formed into a hook d^{16} , substantially as and for the purpose set forth.

In testimony that I claim the foregoing as my own I have hereto affixed my signature in presence of two witnesses.

FRANK J. WAITE.
